Case Company, Racine, Wis., a corporation

Application June 25, 1942, Serial No. 448,408

17 Claims. (Cl. 171—209)

The present invention relates to magnetos and their component parts and an object thereof is to generally improve the construction and operation of devices of this class. A further and important object of the invention is to improve the impulse coupling portion of a magneto.

More particularly an object is to provide for adjusting the point at which the impulse takes place and also to provide for positively maintaining such adjustment.

A further object is to provide a novel flange mounting for a magneto and for isolating the interior of the magneto from communication through the flange, with the interior of the engine with which the magneto is used.

The manner in which this is accomplished is fully set forth in the following specification and accompanying drawings in which a satisfactory embodiment of the invention is shown. It is to be understood that the invention is not limited to the details disclosed but includes all such variations and modifications as fall within the spirit of the invention as herein expressed.

In the drawings,

Figure 1 is a vertical axial sectional view of a magneto embodying the invention.

Fig. 2 is an enlarged detail of certain structure indicated in Fig. 1.

Fig. 3 is an elevation of an impulse coupling taken from the left in Fig. 1.

Fig. 4 is a front elevation of a portion of Fig. 1 with parts removed and others broken away.

Figs. 5 to 10 are sectional views taken on the line 5—5 of Fig. 1, showing the parts in various progressive positions constituting a cycle of operation.

Fig. 11 is a sectional view on the line 11—11 of Fig. 1.

Fig. 12 is a similar view of a modified construction.

As seen in Fig. 1, the magneto illustrative of the invention comprises a body portion 10 including a flange 11 adapted for connection to a complementary flange 12 comprising a part of an engine which drives the magneto and for which the magneto supplies the ignition spark. A coupling portion 13 within flange portion 12 is driven from the engine and actuates the magneto as will appear. The body portion 10 is closed at its top by an upper cover 14 and at its rear by an end or distributor cover 15, the several parts forming a weather-proof and in fact substantially fluid-tight inclosure for the working parts of the magneto.

The magneto has a main shaft or spindle 16 on which is mounted a rotor 17, in the present instance being the magnetized element of the magneto, and said shaft is mounted in anti-friction or other suitable bearings generally des-

ignated as 18 and 19 which support the shaft for rotation.

Bearings 18 and 19 are preferably of the sealed, permanently lubricated type of which numerous examples are well-known. An illustrative or preferred embodiment of bearings 18 and 19 may be constructed as shown in Fig. 2. In this construction each bearing has an outer race 20, a series of balls 21 and an inner race 22. Outer race 20 in the present illustrative bearing is grooved and receives annular shielding plates 23 and 24 substantially closing the space between the races and enclosing balls 21. Shields 22 and 24 are preferably tight in outer race 20 but do not contact inner race 22, the slight space between the two being closed by sealing members 25 and 26 of suitable resilient or elastic material. The space about balls 21 is charged with a quantity of lubricant and which is prevented from escape by shields 23 and 24 and sealing means 25 and 26. The latter also effectively prevent the entrance of dirt, water, or other deleterious material into the bearings.

Bearings such as this will run for very long periods without attention.

Shaft 16 carries a breaker cam 27 for actuating the breaker points, not shown, a gear 28 meshing with a gear 29 for driving the distributor disk 30 all in well-known manner.

Magnet 17 rotates between pole pieces, one of which is indicated at 31 and which cooperate with a core portion 32 within a coil 33 for developing the necessary high voltage in well-known manner.

Shaft 16 is driven through an impulse coupling generally designated as 34 in the present instance within flange 11.

The space to the right of flange 12 is commonly open to the crank case of the engine although it is contemplated that it may be sealed therefrom by a partition 35, an oil retainer 36 of any suitable type closing the space about a drive shaft 37. Shaft 37 drives coupling 34 which in turn drives shaft 16. Shaft 16 must therefore pass within housing 10 which makes possible the inadvertent transmission of vapors, gases, etc., prevalent in the crank case into housing 10. In the present construction, this is prevented as follows.

As above described, bearing 19 is sealed against the exit of lubricant or entrance of foreign material. Housing 10 and flange 11 are constructed with an opening 38 in the present instance downwardly open to the external atmosphere and extending upwardly to surround shaft 16. Spaced from bearing 19 an oil seal of suitable or well-known type 39 engages shaft 16 to close opening 38 from the interior of flange 11. Thus any vapors, oil, or the like, within flanges 11 and 12 are prevented from escaping into opening 38.

Seals such as 33 are very effective but are subject to wear under certain conditions. In case any oil or other material escapes past seal 39, in any manner, it is promptly thrown off by a flinger 40 surrounding shaft 16 and drained out through opening 38. In this way any crank case oil is kept away from bearing 19. Thus although bearing 19 is sealed and ordinarily would prevent the entrance of such crank case oil, the possibility of failure of the seal because of the impurities in the crank case oil is effectively avoided.

Magneton of this general type are subjected to extreme fluctuation in temperature and at the same time it is undesirable to provide any ventilation of the interior thereof for known reasons. Such temperature changes may possibly result in such changes of pressure of the air within housing 10 as to force air through the seal about bearing 19. Thus, if air is forced out when the magneto is hot, it follows that air may possibly be drawn in when the magneto cools. If this does occur, the air which finds its way into housing 10 will be clean outside air drawn in through opening 38. In the past, in known constructions, crank case vapor containing acid and other damaging substances, has been drawn from the crank case into the magneto housing by an analogous action. This action is effectively prevented by the construction described including opening 38.

Magneton in general depend upon a certain velocity of rotation in order to generate a suitable voltage for furnishing an ignition spark, and it is ordinarily inconvenient to produce such velocity under cranking conditions. Accordingly it is common to accelerate momentarily the rotation of the magneto parts at the instant the spark is needed by means of an "impulse coupling."

Impulse couplings of known type have been subject to failure for several reasons and also have been difficult to adjust in order to obtain the impulse spark at the required retarded point in the engine cycle for most favorable starting conditions. Furthermore, they have been expensive to construct. In the present instance, an impulse coupling has been devised which overcomes these difficulties. Impulse coupling 34 is built largely on a hub portion 41, which is a part readily made in quantity on automatic machinery. The remaining parts of the coupling are so devised that they can be readily made by inexpensive stamping operations. In this way, a coupling is provided which is substantially less expensive than heretofore known constructions. The coupling also has certain advantages in operation and in durability over heretofore known devices, the features responsible for these advantages being as follows:

The coupling comprises a driving element generally designated as 42 rotatably mounted on hub 41 and which drives, through a spring 43 a driven element generally designated as 44 fixed on hub 41. Spring 43 tends to rotate driven element 44 in a forward direction, maintaining it against stop portions 45 and 46 carried by member 42. The driving and driven elements therefore rotate in unison in fixed relation to each other under normal running conditions. When the engine is being cranked and therefore turning substantially slower than its normal speed, driven element 44 is momentarily retarded, as will appear, so as to lag behind stop members 45 and 46. At the time the spark is required, member 44 is released whereupon spring 43 causes an extremely rapid partial rotation of member 44 until it again en-

gages stops 45 and 46. During this rapid partial rotation the other magneto parts operate in well-known manner to produce the spark. This spark normally starts the engine after which member 44 is steadily rotated in contact with stops 45 and 46. The speed of rotation is then high enough to generate the spark so that it is unnecessary to accelerate member 44 by means of spring 43.

Member 44, as best seen in Fig. 3, comprises a disk like element providing slots 47 and 48 extending circumferentially and spaced inwardly from the periphery of the disk. In the present instance, the slots open into outwardly directed notches or recesses 49 and 50. Disk or driven member 44 forms a rear wall against which is disposed above mentioned driving member 42. The latter comprises a cup like element 51, Fig. 1, journaled on a forward portion of hub 41 and rotatably engaged about the periphery of a disk 52. Thus driving member 51 is free to rotate relatively to hub 41 and driven member or disk 44. Stops 45 and 46 in the present instance are in the form of tongues extending rearwardly from the rim of cup like member 51 through slots 48 and 47 respectively.

For interrupting the rotation of driven member 44, in the present instance, pawls 53 and 54 are journaled on pins 55 and 56 and have counterweights 57 and 58 disposed peripherally on the opposite sides of pins 55 and 56 from pawls 53 and 54. The pawls are very freely journaled on pins 55 and 56 so as to be influenced by gravity and centrifugal force. Thus in the position shown in Figs. 1, 3, 4 and 5, counterweight 57 has dropped by gravity and swung pawl 53 outwardly of the periphery of disk 44. As the engine is cranked and coupling 34 rotated, in the direction indicated, driving member 42 and driven member 44 will rotate together, being held so by spring 43, until pawl 53 encounters an abutment generally designated as 59. This stops the rotation of disk 44 through pin 55, whereupon tongues 45 and 46 continue to rotate in slots 48 and 47 as more particularly seen in Fig. 6, thus further increasing the tension in spring 43. At a predetermined point, tongue 46 encounters pawl 54 which has been resting against abutment 59 and presses pawl 53 inwardly out of engagement with abutment 59, as indicated in Fig. 7. Disk 44, urged by spring 43, immediately starts to overrun driving member 42 thus initiating the desirable momentary rapid rotation of driven member 44. In Fig. 8, disk 44 has acquired substantially its full velocity and has nearly regained its original relation with tongues 45 and 46. The relative velocities of the two parts, driving and driven are indicated roughly by the length of the arrows showing the direction of rotation. The velocity of member 44 is sufficient to generate a positive spark for starting the engine. In Fig. 9, disk 44 has completely caught up with tongues 45 and 46 and the impulse action is completed. The engine has started, however, and the velocity of tongues 45 and 46 has increased roughly to that indicated by the arrow in Fig. 9. Centrifugal force now holds counterweights 57 and 58 in their extreme outward position so that pawl 54 which is now approaching abutment 59 will be retracted and will not engage the abutment. This is clearly shown in Fig. 10 in which pawl 54 is shown clearing abutment 59 by a generous amount. Pawl 53 also clears the abutment under these conditions as will be apparent.

As will now be clear, pawl 54 would operate in

substantially the same manner if the engine were cranked from a position where pawl 54 instead of pawl 53 was approaching abutment 59.

Abutment 59 as above stated is normally stationary but it will be apparent that the point in the rotation at which the pawls engage the abutment will determine the point in the cycle of the engine at which the starting spark occurs. In the present instance the location of abutment 59 is adjustable as will appear for the purpose of obtaining the desired timing of the starting spark.

Returning to a more detailed description of the parts, driving member 42 comprises a cup like member, as above stated, and has openings 60 and 61 through which project dogs 62 and 63 for engagement with slots 64 and 65 in above mentioned coupling member 13. In the present instance, dogs 62 and 63 are formed from a pair of C-shaped elements 66 and 67 disposed within cup like member 51. Member 66 has tongues 68 and 69 projecting forwardly through openings 60 and 61 respectively while member 67 has tongues 70 and 71 projecting forwardly also through openings 60 and 61, although it is contemplated that dogs 62 and 63 might be made in one piece in the form of return bends, instead of in the two parts 68-70 and 69-71, respectively. Tongues 68 and 70 constitute dog 62 while tongues 69 and 71 constitute dog 63. Member 66 is held in place in cup like element 51 in the present instance by rivets as 72 engaged in suitable holes as 73 in members 51 and 66. In like manner, rivets as 74 and holes as 75 secure member 67 within member 51. Dogs 62 and 63, in this manner, may be fabricated from hardened steel or other suitable material for proper durability and which may be quite different from the material of cup 51 which would require, for example, certain particular working characteristics.

Cup like element 51 is prevented from moving axially on hub 41 by a washer or similar element 76 clamped against the end of hub 41, for example, by a nut 77 threaded on a portion 78 of above mentioned shaft 16. The pressure of nut 77 also holds hub 41 in place on a tapered shank portion 79 of shaft 16. A key 80 seated in shank portion 79 and engaging a keyway 81 maintains hub 41 and shaft 16 in the required relation.

Pins 55 and 56 in the present instance constitute the means for uniting the several parts of driven member 44 with hub 41. Thus pin 55 has a reduced shank portion 82 passing through disk 44, a spacer disk 83 and above mentioned disk 52. Hub 41 has a shoulder 84 against which the several disks 44, 83 and 52 are seated. A disk 85 is seated on the opposite side of shoulder 84 and urged toward disk 52 by above mentioned shank portion 82 which in the present instance is riveted or otherwise suitably fastened to disk 85. An identical construction is associated with above mentioned pin 56 and which it is not considered necessary to describe in detail. In this manner, the several disks are solidly mounted on hub 41. As seen in Fig. 3, hub 41 has flattened portions 86 and 87 for positively preventing rotary shifting of the parts relatively to the hub under the considerable shock loads developed by the action of the coupling. Other non-circular shapes are contemplated as within the scope of the invention.

It is to be noted that pawls 53 and 54 are very freely journaled on pins 55 and 56 so that

there will be no possibility of their failing to rock about these pins under the action of gravity and centrifugal force, and washers 87a and 87b are preferably interposed between pawls 53 and 54, and disk 44 to prevent dragging of the pawls or counterweights on disk 44.

As a further precaution against dragging or sticking, counterweights 57 and 58, as seen in Fig. 3, are indented at 87c and 87d so as to provide raised points 87e and 87f, Fig. 7. These points normally clear disk 44, but in the event of contact, prevent any appreciable area of the weights coming against the disk so as to minimize any tendency toward sticking, particularly if the parts are coated with cold oil.

Spring 43 is anchored in a channel-like fitting 88, Fig. 4 in the present instance united with the exterior of cup like member 51 in any suitable manner as by welding, and in the present instance has a hook portion 89 engaged about a lip 90 turned back, from a portion of channel 88. An ear 91 is bent about spring 43 and positively prevents disengagement of the spring from the channel member regardless of speed of rotation or other influences. In a similar manner, the opposite end of spring 43 is engaged in a channel portion 92 on a portion of disk 44, a similar hook portion 93 engaging a tongue 94 to positively hold the end of the spring. Channels 88 and 92 support the end portions of the spring wire against excessive distortion and thereby distribute the flexing more or less evenly throughout the length of the spring.

Spring 43 being outside of the rest of the coupling operates at the greatest possible radius and accordingly effects the most rapid acceleration possible for a given torque value in the spring. An exceedingly rapid "snappy" acceleration is thereby obtained in the driven element.

Abutment 59 in the present instance is part circular in shape and struck up from a plate 95 engaged within flange 11 as more particularly seen in Fig. 11.

The shape of abutment 59 is such that the plane tangent to the abutment and containing the point of contact between the pawls and the abutment, is substantially at right angles to the line of thrust from the pivots or pins 55 and 56 to the point of contact. In this way, any tendency toward slipping off of the pawls is avoided. Furthermore, engagement of the pawls is not dependent on sharp corners, and what wear is induced by enormous numbers of operations will not alter the surfaces sufficiently to change the above relations appreciably, or cause failure of the pawls to remain engaged until disengaged by the tongues.

Plate 95 has a plurality of teeth 96-96 extending from the periphery thereof and which are engageable with teeth 97-97 formed in the periphery of a recess 98 in the back wall 99 of flange 11. Thus an exceedingly strong connection is provided between plate 95 and flange 11 so that inadvertent shifting of abutment 59 is impossible. Plate 95 is held in recess 98 in any suitable manner, in the present instance screws 100-100, engaged in wall 99, engaging the edges of plate 95 to prevent axial displacement thereof.

Axial displacement, therefore, being impossible, plate 95 cannot be shifted except deliberately by removing screws 100, lifting the plate out of recess 98 and reinstalling it in the desired position. With screws 100 replaced, plate 95 then cannot shift from its new position. The position of abut-

75

ment 59 is thus readily adjustable, but it cannot shift accidentally once the adjustment is made.

In adapting a magneto to various types of engines, plate 95 is readily adjusted to the proper position to give the most desirable amount of lag or retard to the spark desirable for starting that particular type of engine. For this purpose, a pointer 101 is provided on plate 95 which registers with one or another of notations 102 according to the position in which plate 95 is installed. In practice, therefore, the degree of lag of the impulse coupling can be determined in advance by properly seating plate 95 according to notations 102. In the present instance, the teeth in recess 93 are spaced at increments of 5° which is close enough for substantially ideal settings of abutment 59. Teeth 96 are not necessarily set at the same increments, in the present instance being spaced at 10° which facilitates the assembling of the parts particularly in the event of slight inaccuracies in the stamped plate. Notations 102 and pointer 101 are visible past disk 44 when the magneto is removed from flange 12. Thus the starting lag of a particular magneto may be determined at a glance without any testing or extraneous apparatus of any kind.

In some instances, it is desirable to mount a magneto in various positions other than vertical and as will be apparent this will necessitate relocating of abutment 59, perhaps beyond the range of adjustment possible in the embodiment of Fig. 11. Thus in aircraft practice, magnetos are frequently located up-side-down as related to the showing in Fig. 1, or possibly 90° from such showing. The invention facilitates such use as shown in the modification of Fig. 12. In this arrangement, a recess 103 is provided with teeth 104—104 corresponding in general to above mentioned teeth 97 but extending completely around the periphery of recess 103. Plate 95 may therefore be located in recess 103 in any position whatever within the increments determined by teeth 104. In this embodiment it would be inconvenient to utilize screws as 100 and accordingly a snap ring 105 is located in a groove 106 within a modified flange 107 and maintains plate 95 in adjusted position. Plate 95 may be located wherever necessary in view of the position of the magneto after which ring 105 is allowed to expand into groove 106 and will maintain the adjustment. Compensation is made in the other parts of the magneto for the new relative location of the impulse or tripping point as is well understood.

In magnetos of high power, it is essential to separate parts carrying the high output voltage appreciable distances from the metal parts of the magneto and at times this is difficult because of space limitations. Thus, if the voltage is such that the spark will jump for example, 3/4" all metal parts must be separated at least this distance from any high voltage conductor unless separated therefrom by rugged insulation. Since the magneto must be made so that it can be taken apart, it is difficult to obtain this spacing between all parts and the exposed conductor. In the present instance an auxiliary insulating member 108 in the form of a sheet of dielectric acetate is interposed about coil 33 and between it and pole pieces 31 and frame 10. This adds greatly to the efficiency of the insulation associated with coil 33 and forms a barrier against stray discharges from coil 33 to the adjacent metal parts of the magneto.

The above being a complete description of the

construction and operation of an illustrative embodiment of the invention, what is claimed as new and desired to be secured by Letters Patent of the United States is:

5. 1. In a magneto, a housing portion and a flange adapted for mounting on an engine and in supporting relation to said housing portion, said housing portion providing a downwardly directed vent opening, a shaft extending from said magneto housing portion through said flange for driving said magneto, said opening being arranged so as to expose said shaft between the interior of said magneto housing and said engine, sealing means about said shaft at one side of said recess, a flinger on said shaft within said recess, and sealing means at the other side of said recess.
- 10 2. In combination with an engine having a crank case, a magneto including a housing, a shaft in the housing, a member on the shaft within the housing rotatable with the shaft, a bearing within the housing supporting the shaft for rotation, sealing means on the shaft spaced from the bearing, a flange on the housing and adapted to be mounted on the engine to support said magneto in communication with said crank case, coupling means on the shaft beyond said sealing means as related to said bearing and through which said magneto is driven from mechanism within said crank case, and said housing being 15 so shaped as to provide a draining recess extending from said shaft between said bearing and said sealing means to the outside of said housing.
- 20 3. In a magneto having a housing and a shaft in the housing, the combination of a rotor on the shaft, a bearing supporting the shaft for rotation 25 in the housing, sealing means on the shaft spaced from the bearing, a flange on the housing spaced from the sealing means and adapted to be mounted on an engine, coupling means on the shaft beyond the sealing means, and said housing being 30 so shaped as to provide a recess extending from said shaft between said bearing and said sealing means to the outside of said housing.
- 35 4. In a magneto including a housing portion and an impulse coupling associated with said housing portion and including a plate, an abutment on said plate positioned to engage parts of said coupling, means for tripping the latter to produce an accelerated movement in said magneto, interlocking teeth on said plate and said housing adapted to positively prevent rotation of said plate, said teeth being disengageable from each other by axial movement of said plate for 40 rotation and installation in another position, a screw engaged in said housing and having a head overlapping said plate for preventing axial displacement of said plate for maintaining the adjustment thereof, and dial and pointer means on 45 said plate and said housing for indicating the effect on the impulse timing of installation of said plate in various positions.
- 50 5. In an impulse coupling including a housing portion and a rotative portion, an abutment carrying element, an abutment on said element positioned to engage parts of said rotative portion for preventing rotation thereof, means for tripping said parts to produce an accelerated movement in said magneto, disengageable means for holding said abutment carrying element in said housing portion, interlocking surfaces on said element and said housing portion positioned to 55 positively prevent rotation of said element independently of said holding means, said surfaces being disengageable from each other by axial 60 movement.
- 65 6. In an impulse coupling including a housing portion and a rotative portion, an abutment carrying element, an abutment on said element positioned to engage parts of said rotative portion for preventing rotation thereof, means for tripping said parts to produce an accelerated movement in said magneto, disengageable means for holding said abutment carrying element in said housing portion, interlocking surfaces on said element and said housing portion positioned to 65 positively prevent rotation of said element independently of said holding means, said surfaces being disengageable from each other by axial 70 movement.
- 75 7. In an impulse coupling including a housing portion and a rotative portion, an abutment carrying element, an abutment on said element positioned to engage parts of said rotative portion for preventing rotation thereof, means for tripping said parts to produce an accelerated movement in said magneto, disengageable means for holding said abutment carrying element in said housing portion, interlocking surfaces on said element and said housing portion positioned to 75 positively prevent rotation of said element independently of said holding means, said surfaces being disengageable from each other by axial movement.

movement of said element for rotation and installation in another position upon disengagement of said holding means.

6. In a magneto, including a housing portion and an impulse coupling associated with said housing portion, a plate, an abutment on said plate positioned to engage parts of said coupling, means for tripping the latter to produce an accelerated movement in said magneto, interlocking teeth on said plate and housing portion, having surfaces extending substantially in the direction of the axis of said impulse coupling, and adapted to positively prevent rotation of said plate, said teeth being disengagable from each other by axial movement of said plate for rotation and installation in another position, a screw engaged in said housing and having a head overlapping said plate for preventing axial displacement of said plate for maintaining the adjustment thereof, and dial and pointer means on said plate and said housing for indicating the effect on the impulse timing of installation of said plate in various positions.

7. In an impulse coupling, including a housing portion, a plate, an abutment on said plate positioned to engage parts of said coupling for preventing rotation thereof, means for tripping said parts to produce an accelerated movement in said magneto, interlocking surfaces on said plate and housing substantially parallel to the axis of said impulse coupling adapted to positively prevent rotation of said plate, said surfaces being disengageable from each other by axial movement of said plate for rotation and installation in another position, and means for preventing inadvertent axial displacement of said plate for maintaining the adjustment thereof.

8. In an impulse coupling for a magneto for mounting on an engine, a driving element comprising a cup like member and a C-shaped element within the cup like member and having outturned ends projecting through the wall of the cup like member toward said engine and forming driving dogs to receive the drive from the engine with which the magneto is associated.

9. In an impulse coupling for a magneto, a driving element comprising a cup like member and an element disposed within the cup like member, and having an outturned portion projecting through the wall of said cup like member to form a driving dog to receive the drive from an engine with which said magneto is associated.

10. In an impulse coupling opposed axially spaced driving and driven members, said driven member being rotatable relatively to said driving member, stop means on said members adapted to maintain them in fixed rotative relation to each other, and spring means coiled about the outside of said members, having opposite ends connected respectively to opposite members and tensioned to yieldingly maintain said stop means in contact for driving said driven member from said driving member.

11. In an impulse coupling, opposed axially spaced driving and driven members, said driven member being rotatable relatively to said driving member, stop means on said members adapted to maintain them in fixed rotative relation to each other, a channel on one of said members and a spring engaged in said channel and having its opposed ends connected respectively to opposite members and tending to yieldingly

5 maintain said stop means in contact for driving said driven member from said driving member.

12. In an impulse coupling a driven member comprising a hub having a flange or shoulder intermediate the ends thereof, a driven disk on one side of said flange, an anchoring disk on the other side of said flange, a plurality of pins carried by said disks, pawls journaled on said pins for actuating said impulse coupling, and said pins being adapted to unite said disks and to clamp them into intimate contact with said flange.

13. In an impulse coupling, a driven member comprising a hub having a flange or shoulder intermediate the ends thereof, a driven disk on one side of said flange, an anchoring disk on the other side of said flange, and tension means uniting said disks and clamping them into intimate contact with said flange.

14. In an impulse coupling, a driven member, including a hub, a disk on the hub, a second disk adjacent the first disk and having an outer periphery adapted to constitute a bearing portion, a journal portion on said hub and spaced from said disk, and a driving member comprising 20 a cup-like element journaled on said journal portion and on the second mentioned disk, a tongue on said cup-like element extending beyond the first mentioned disk, a stop on said first mentioned disk, and spring means connected for holding said tongue yieldingly in contact with said stop.

15. In an impulse coupling having a disk-like driven element, a pin on said disk-like element, a pawl pivoted on the pin, and a counterweight 35 element connected with the pawl and disposed on the opposite side of said pin from said pawl, and a relatively small raised portion on one of said elements positioned to prevent extended area contact between said counterweight element and said disk element.

16. In an impulse coupling, opposed axially spaced driving and driven members, said driven member being rotatable relatively to said driving member, stop means on said members adapted to maintain them in fixed rotative relation to each other, a channel on one of said members, a spring wire engaged in said channel and having a hooked portion at one end, a lip associated with said channel and engaged with said hook portion for anchoring said spring wire in said channel, and said spring wire having its opposed ends connected respectively to opposite members and tending to yieldingly maintain said stop means in contact for driving said driven member from said driving member.

17. In an impulse coupling, opposed axially spaced driving and driven members, said driven member being rotatable relatively to said driving member, stop means on said members adapted to maintain them in fixed rotative relation to each other, a channel on one of said members, a spring wire engaged in said channel and having its opposed ends connected respectively to opposite members, an ear on said channel shaped to enclose a portion of said spring wire to prevent dislodgement of the wire from said channel, said wire having its opposed ends connected respectively to opposite members and tending to yieldingly maintain said stop means in contact for driving said driven member from said driving member.
